UNITED STATES PATENT OFFICE

160,827

INCIDENT LIGHT ADAPTER FOR PHOTO-ELECTRIC EXPOSURE METERS

Alexander T. Williams, Westfield, N. J., assignor
to Weston Electrical Instrument Corporation,
Newark, N. J., a corporation of New Jersey

Application August 9, 1948, Serial No. 148,007

Term of patent 14 years

(Cl. D61—1)

To all whom it may concern:

Be it known that I, Alexander T. Williams, a citizen of the United States of America, residing at Westfield, county of Union, State of New Jersey, have invented a new, original, and ornamental Design for an Incident Light Adapter for Photoelectric Exposure Meters, of which the following is a specification, reference being had to the accompanying drawings, forming part hereof, and wherein:

Fig. 1 is a perspective view of an incident light adapter for photoelectric exposure meters, showing my new design;

Figs. 2 and 3 are top and bottom views, respectively, of the same;

Fig. 4 is a side elevation;

Fig. 5 is a rear elevation; and

Fig. 6 is a transverse section through the adapter as taken on line 6—6 of Fig. 2.

The essential features of my design reside in the parts shown in full line.

I claim:

The ornamental design for an incident light adapter for photoelectric exposure meters, as shown and described.

ALEXANDER T. WILLIAMS.
